UNITED STATES PATENT OFFICE.

ALLEN GARDINER INGALLS, OF LAPRAIRIE, QUEBEC, CANADA.

FURNACE.

935,759.

Specification of Letters Patent.

Patented Oct. 5, 1909.

Application filed August 27, 1906. Serial No. 332,265.

To all whom it may concern:

Be it known that I, ALLEN GARDINER INGALLS, a subject of the King of Great Britain, residing at the town of Laprairie, 5 in the county of Laprairie, in the Province of Quebec, in the Dominion of Canada, have invented certain new and useful Improvements in Furnaces, of which the following is a specification.

10 This invention relates to improvements in furnaces, as described in the present specification and illustrated by the accompanying drawings that form part of the same.

15 The invention consists essentially of the novel construction and arrangement of parts, whereby the circulating water is heated between outer and inner shells and the fire supported on a close fire pan at the bottom of said inner shell.

20 The objects of the invention are to apply a simple and known form of fire box to a hot water heating apparatus, to simplify and thus lessen the cost of hot water furnaces, and to devise a type of furnace in 25 which sure combustion is assured and consequently economy in the consumption of fuel effected.

25 In the drawings, Figure 1 is a perspective view of the furnace complete. Fig. 2 is a vertical section of the furnace. Fig. 3 is a perspective view of the inner casing showing the fire box and flue. Fig. 4 is a cross sectional view through the line A—B, in Fig. 2. Fig. 5 is a sectional detail of a portion of 35 the furnace casing showing the feed opening and door in its open position.

Referring to the drawings, *a* is a base of inverted pan shape having the pipe openings *b* and *c* through the top thereof to the 40 rear of the portion *45*, the latter forming the bed of the fire box or otherwise "a close fire pan", the expression "said close fire pan" conveying the meaning of a fuel support without draft openings therethrough. *e* and 45 *f* are openings through the side wall of said base. *46* are bolt holes through the top of said base in proximity to said side wall.

50 *g* is the inner shell of the furnace, the front wall *h* of which forms the front wall of the fire box *j*, while the rear and side wall *i* of said fire box is formed by an extension rearwardly from said front wall *h* joining the reverberatory flue *k* toward the top end of said fire box *j*, the said reverberatory flue con-

tinuing downwardly to the base *o*, the latter 55 forming a support for the said inner shell. The reverberatory flue *k* at its lower curve has the opening *r* leading thereinto from a corresponding opening *q* in the base *o*, the latter registering with the opening *c* in the 60 main base *a*. The reverberatory flue *k* continues upwardly and extends along over and forms the top of the fire box *j*, the egress opening *l* from said flue being through the upper end of the front wall *h* of said inner 65 shell. *m* is the feed opening to said fire box through said front wall *h* immediately below the opening *l*. *n* is an opening at the lower end of said wall *h* forming the damper opening and also an opening for the removal 70 of the ashes in the lower end of the fire box. The walls *h* and *i*, as also the lower end of the reverberatory flue, rest on the said base *o* and preferably in construction form part therewith, the said walls *h* and *i* terminating 75 at the edge of an opening *p* corresponding in size to the fire pan *45*, though it must be understood that this base can be completely closed in and form a fire pan in itself in place of building the fire on the main base *a*. 80 *u* are bolt holes adjacent to the edge of the base *o* and registering with bolt holes *46* through the main base *a* on which the said base *o* is supported. At the upper end of the said reverberatory flue *k* and at the beginning of that portion thereof, where the said flue *k* extends over the fire box, a suitable opening therefrom leads to the pipe *w* closed by the cap *11*. *w* is an opening into said flue at the top end of said fire box *j*, a seat *x* being formed around the said opening *w*. The bases *a* and *o* are securely bolted together 85 through the bolt holes *46* and *u*, as explained hereinafter, so that the fire box *j* is thus made complete with the exception of the 90 necessary doors and dampers, the passage for the hot gases being over the top of the wall *i* into said reverberatory flue *k* and on through said flue over the top of said fire box out through the opening *l* into the 100 chimney *13*. *y* is a pipe extending through the opening *c* in the wall of the main base *a* under the fire box and leading to the openings *q* and *r*, the said pipe being for the purpose of inserting a cleaning instrument 105 for clearing out the lower end of said flue. *z* is a cap closing the outer end of said pipe *y*. *2* is the outer shell preferably dome-

shaped and having the vertical reinforcing ribs 3 terminating at their lower ends in the flange 4. 43 are bolt holes through the said flange 4 registering with the bolt holes 5 45, the said flange 4 of the outer shell 2 resting on the base *o* of the said inner shell, and the three, that is to say, the outer shell 2 through its flange 4, the base *o* and the main base *a* being securely fixed together by the bolts 5 extending through said bolt holes.

It has already been stated that the main base and the base *o* are secured together by bolts, but it must be understood that in this construction the three parts are all secured 15 by bolts.

The outer shell 2 has an opening at the front thereof corresponding to the shape of the front wall *h* of the inner casing and surrounding the same. 6 is a panel closing the 20 front opening to said outer shell and securing said outer shell and said inner shell together by means of the bolts 7 extending through said panel 6 into and through the wall *h* of the said inner shell. The panel 6 25 has openings corresponding to the openings in the wall *h*, the opening 12 registering with the flue opening *l*, the pipe 13 extending therefrom, and the opening 14 registering with the feed opening *m*. Again said 30 outer shell has an opening 9 through which the pipe *v* from the inner shell extends, the gland 10 being formed around the junction of the said pipe *v* and the said outer shell.

15 is a door frame extending inwardly 35 through the feed openings 14 and *m* and having the sides 17 receding from their lower ends, said walls forming the inwardly projecting shoulders 18 beyond the inner face of the wall *h*. The base 16 of the door 40 frame 15 slants downwardly and is secured to the panel 6 by means of the bolts 20 inserted through the flange 19, the latter extending downwardly from said door frame base. 21 is a door hinged to the outer edge of the 45 base 16 of said door frame and having the lug 22 projecting from its outer surface and an orifice 23. 24 is a link pivotally secured to the lug 25 projecting outwardly from the flange 19. 26 is a rod curved at its lower 50 end and pivotally secured at the lower end of the link 24 and to the lug 22. 27 is the door handle having its shank 28 extending inwardly therefrom through the said orifice 23.

55 29 is a cam fixedly secured to the inner end of the shank 28.

30 is a plate forming a damper hinged to the outwardly projecting part 31 of the flange 32, the latter extending upwardly 60 from the door frame 15 and the said plate or damper 30 resting in its lower position on the shoulders 18 forming part of the door frame.

65 The door in its open position rests on the rod 26, the link 24 turning to its lower posi-

tion. On the closing of the door 21 the link rises to its upper position beneath the base 16 and a curved portion of the rod 26 extends around the hinge of the door. On the action of closing the door, the handle 27 is 70 turned in order to lock it to its closed position and as the said handle is turned, the cam 29 engages the lower face of the plate or damper 30 and raises said plate or damper 30 into engagement with the seat *x*, thus 75 closing the opening *w*.

33 is a door frame of somewhat similar construction to the door frame 15 with the exception that the base 34 preferably extends in a straight line outwardly from the 80 interior inner surface of the fire box and is supported by the pieces 35. The sides of said door frame are joined at the top by the piece 37, from which the flange 38 extends upwardly and is secured to the panel 6. 85

39 is a door hinged at the outer edge of the top piece 37 and having a suitable handle 40 attached to the lower edge so that the said door may be raised for the purpose of increasing the draft and removing ashes from 90 the fire pan.

41 is a pipe extending through the opening *f* in the side wall of the base and suitably elbowed and connected to the pipe *t* at its inner end and at its outer end to a suitable water supply, the pipe *t* leading under said base to an opening *s* into the water chamber formed between said inner and outer shell and surrounding said fire box 95 and flue.

50 is an outlet opening from the outer shell 2. 42 is a pipe leading from said outlet opening to the heating pipes.

The use of this device will be readily understood from the description of the parts, 105 as the water entering through the inlet opening *s* fills the space between the inner and outer shells, and then circulates throughout said space and the heating pipes.

This invention is the adaptation of an old 110 form of heater to a hot water heating furnace construction and though in some parts of the country, said old form of heater is largely used and appreciated, its application to a modern method of heating houses and buildings has not been made hitherto. In this form of heater, fire is built on, what may be termed, the ground, though this may be more clearly explained by saying that it is built on a "close fire pan", a bottom to the 115 fire box without draft openings therethrough. The fire box in itself is preferably in a form of tube, in which fuel is fed on top of the fire burning in the bottom of said box and the ashes simply removed from the 120 fire box itself at a lower door.

In this form of furnace there is quite a heating surface and this heating surface is added to by the reverberatory flue, though the said reverberatory flue is not actually 125 130

necessary to the invention, though it is preferably included in the construction.

What I claim as my invention is:

1. In a furnace, the combination with an inner shell having suitable openings thereinto and a close fire pan at the bottom end thereof, of an outer shell supported by said inner shell and having suitable corresponding openings to said inner shell, one of said openings forming a feed opening, another a flue opening and another an ash remover and damper opening, at the bottom end of said fire box and above the fire pan, substantially as described.
2. In a furnace, the combination with an inner shell and a base supporting said inner shell, the latter forming a close fire pan, of an outer shell inclosing said inner shell and supported thereby, bolts securing said outer shell, said inner shell and said base together, said shells having corresponding inlet and outlet openings, corresponding feed and ash remover openings and corresponding flue openings, and glands formed around the adjoining parts of said shells at the various openings thereto and therefrom, substantially as described.
3. A furnace, comprising a base, having orifices therethrough and for a portion of its surface forming the solid bed bottom of the fire box, an inner casing mounted on said base forming the inclosing wall of the fire box and a reverberatory flue directly connected thereto, said flue having an opening at the lower bend thereof in alinement with an orifice in the said base, and a branch pipe therefrom at its upper end, said casing having suitable openings to said fire box and into said flue, an outer casing having corresponding openings to said inner casing and an opening at the top thereof through which said branch pipe extends and a water inlet through one of the orifices in the base and a water outlet at the upper end thereof, said outer casing inclosing the water chamber around said flue and fire box, a gland formed at the joining of said pipe and said outer casing, and means for closing said fire box openings, as and for the purpose specified.
4. A furnace, comprising a base having suitable orifices therethrough and for a portion of its surface forming the solid bed bottom of the fire box, an inner casing forming the inclosing walls of said fire box and having a squared front and openings through said squared front to said fire box and a reverberatory flue leading from the upper end of said fire box and terminating above said fire box at an outlet through said squared front and having an opening at the lower bend thereof in alinement with an orifice through said base and a branch pipe from the upper portion thereof, an outer dome-shaped casing forming a water chamber around said fire box and flue and having an opening at the top thereof through which said branch pipe extends and a removable panel corresponding to said squared front of the inner casing, said removable panel having openings therethrough leading into said fire box and an opening for said flue, said water chamber having a suitable inlet through one of said orifices in the base and a suitable outlet to the heating coils, a gland formed around said branch pipe at the upper end of the casing, a pipe leading under said base from said lower flue opening and terminating outside said base, and suitable doors closing said openings in said removable panels, as and for the purpose specified.
5. A furnace, comprising a base having orifices therethrough and for a portion of its surface forming a solid bed bottom of the fire box, an inner casing forming the inclosing walls of a fire box and a reverberatory flue leading from said fire box, said inner casing rising from a suitable bed plate and having a squared front and openings through said squared front into said fire box and into said flue, said flue having an opening at the lower bend thereof through said plate and a branch pipe at the upper end thereof, and an opening at the upper end thereof leading directly into said fire box, an outer dome-shaped casing forming a water chamber around said fire box and flue and having a jutting front portion around said flue and an opening at the top thereof through which the said branch pipe extends, a water inlet and outlet and a removable panel corresponding to the squared front of the inner casing and having corresponding openings thereto, door frames introduced into said openings in the fire box, an upwardly folding damper door hinged and adapted to close the opening at the top of said fire box to said flue, doors hinged to said door frame, and a pipe leading under said base to said lower opening in said flue, as and for the purpose specified.
6. A furnace, comprising a base, having orifices therethrough and for a portion of its surface forming the solid bed bottom of the fire box, an inner casing rising from suitable bed plate and forming the inclosing walls of a fire box and a reverberatory flue to the rear of said fire box, said flue having an opening at the lower bend leading through said bed plate and a branch pipe at the upper end thereof and an opening thereinto directly over said fire box, said fire box having its front wall squared and an opening to the flue at the upper end thereof and immediately below a feed opening to the fire box and at the lower end an ash and draft opening, a dome-shaped casing supported by said base and forming a water chamber around said fire box and flue and having an opening at the top thereof through which said branch pipe extends and a removable panel corresponding to the squared front of the inner casing, said removable panel having openings therethrough leading into said fire box and into said flue, said flue having an opening for said branch pipe, said water chamber having a suitable inlet through one of said orifices in the base and a suitable outlet to the heating coils, a gland formed around said branch pipe at the upper end of the casing, a pipe leading under said base from said lower flue opening and terminating outside said base, and suitable doors closing said openings in said removable panels, as and for the purpose specified.

4

pipe extends, a jutting front portion inclosing said flue, a water outlet leading to the hot water pipes and a water inlet leading from the water supply through one of the 5 orifices in said base and a removable panel at the front thereof having corresponding openings to said squared front of the inner casing, a door frame having flanges extending therefrom and secured to said panel and 10 jutting inwardly at the upper end thereof, a door hinged to said door frame and closing the feed opening to said fire box, a damper door hinged at the upper flange of said door frame and closing said opening over said fire 15 box to said flue and adapted to rest on said

inwardly jutting portion of the door frame in its lower position, a door frame arranged in said ash and draft opening, a door hinged to said door frame, and a pipe leading to the opening in the lower bend of said flue, as 20 and for the purpose specified.

Signed at the city and district of Montreal, in the Province of Quebec, in the Dominion of Canada, this 21st day of August, 1906.

ALLEN GARDINER INGALLS.
